SAFETY LIQUID DISPENSER

Alfred T. Harris, Bakersfield, Calif.

Application December 20, 1941, Serial No. 423,712

2 Claims. (Cl. 215—23)

An object of the invention is to provide a liquid container and dispenser for use in hotel bar rooms, cocktail bars or any place where liquor is served.

Another object of the invention is to provide a safety liquid dispenser which shall be of simple construction and therefore of inexpensive manufacture, and yet which will prove thoroughly practical and efficient in use.

Another object of the invention is that the container may be used for any kind of liquid as perfume, medicines etc.

The invention may have a variety of applications and certain of the features of construction may be embodied in a variety of structures.

Other objects, advantages and features of invention may appear from the accompanying drawing, the subjoined detailed description and the appended claims.

The accompanying drawing illustrates the invention.

Figure 1 is a view partly in section and partly in elevation of the invention showing the interior construction and parts therein in position and also shows a portion of liquid therein.

Fig. 2 is a sectional view taken on line 2—2 showing how the glass discs are constructed and shows how they are arranged in a staggered position in the neck of the dispenser.

Fig. 3 is a fragmental detail view partly in section and partly in elevation of a portion of the dispenser body showing one of the positions of the valve and valve weight when the dispenser is in use.

Fig. 4 is a plan view of the valve weight showing the construction thereof.

Fig. 5 is an elevational detail view of the glass staggered discs.

The invention 1 comprises the bottle body portion 2 which is of glass and is provided at its upper end with a tapered neck 3 having a cap 4 that is threaded to the tapered bottle neck 3 at 5.

The lower end of the bottle body 2 is provided with a reduced threaded end 6 to which is threaded a metal cap 7 that is so constructed and arranged to allow room for a series of discs to be interposed between the bottle body end 6 and cap 7 to form a safety seal.

To complete this safety seal the cap 7 is provided with a shoulder 8 upon which rests a copper plate or disc 9 having a hole 10 located in its center that leads into the air space 11.

Placed upon the copper plate 9 is a flexible rubber disc 12, then a tinfoil disc 13 is placed upon the flexible rubber disc 12.

The air space 11 is to prevent creating a vacuum in the bottle to prevent refilling with liquid. If vacuum is created in the bottle the flexible rubber disc 12 expands and bursts the tinfoil disc 5 thus acting as a telltale. The copper plate 9 is to withstand the weight of the liquid 26 and to keep it from going down into the air chamber 11.

Interposed between the valve seat ring 14 and threaded top 5 of the tapered bottle neck 3 and spaced at a distance necessary to permit the flow of liquid are a series of glass discs 16 that are constructed and arranged in a staggered position one above the other to prevent anyone from using an instrument to lift the valve for a refill as shown in Figs. 1, 2 and 5 of the drawing.

A valve 17 is provided that rests upon the shoulders 18 of a valve seat ring 14 that is integral with the lower end of the bottle neck 3 and covers the opening 15 to prevent liquid from passing through and is assisted by the valve weight 19 that is suspended on the valve rod 20 that is guided by the copper guide 21.

The top 22 is of hexagon shape and is provided with grooves 23 that allows passage of the liquid therethrough.

This valve 17 is loosely mounted on the valve rod 20 and the weight 19 may be operated at different angles to open and close the opening 15 as shown in Figs. 1 and 3 of the drawing.

A copper seal 24 is shown at the top of the bottle neck 3 to hold the glass discs in place and cork stoppers 25 are provided to prevent leakage of the fluid.

This container and dispenser is so constructed and arranged that no one can refill with liquid other than the distillery licensed by the government. In the event anyone tries to refill not authorized the telltale means housed in the metal cap 7 will show distinctly by the breaking of the tinfoil disc.

The copper seal 24 is a rod 24a having a slotted head 24b at one end and at the other end a nut 24c.

To apply the seal 24 in the bottle neck the rod 24a would be inserted therethrough and the cork stopper and nut 24c put on and tightened up by using a screw driver inserted in the slotted end after which an outside seal 24d is applied that would indicate and prevent anyone from breaking into or removing the seal 24.

At the bottom of the bottle 2 where the cap is affixed thereto an outside seal is also applied as at 7a.

These outside seals may be of the material

known to the art and to meet any and all legal requirements.

I claim:

1. In a device of the character set forth the combination comprising a bottle body having a tapered bottle neck at its top end and a reduced bottom end; a valve seat ring integral with the lower end of said tapered bottle neck; said valve seat ring having shoulders and being provided with an opening that permits ingress and outgress of liquid when regulated by a valve that rests upon the shoulders of said valve seat ring; said bottle neck being provided with a plurality of glass discs placed in a staggered position to regulate the flow of liquid therein and a metal cap threaded to said reduced bottom end having sealing means encased therein to form a safety seal and telltale.

2. The combination with a bottle body having a tapered bottle neck at its top end and a reduced bottom end and a valve seat ring integral with said lower end of the bottle neck; said valve seat ring having shoulders and being provided with an opening that permits ingress and outgress of liquid when regulated by a valve that rests upon the shoulders of said valve seat ring; said tapered neck of the bottle being provided with a plurality of glass discs constructed in a staggered position one above the other and means comprising a capper seal to hold said glass discs in position so as to regulate the flow of liquid therein and a metal cap threaded to said reduced bottom end and having sealing means encased therein to form a safety seal and telltale.

ALFRED T. HARRIS.
